UNITED STATES PATENT OFFICE.

SYLVAIN ROSENGART, OF PARIS, FRANCE, ASSIGNOR TO LA SOCIÉTÉ DITE: ETABLISSEMENTS L. ROSENGART SIÈGE SOCIAL, OF PARIS, FRANCE.

GENERATOR FOR ELECTRIC LAMPS.

1,416,513.

Specification of Letters Patent. Patented May 16, 1922.

Application filed October 23, 1918. Serial No. 259,415.

To all whom it may concern:

Be it known that I, SYLVAIN ROSENGART, citizen of the Republic of France, and resident of Paris, France, (post-office address 5 7 Avenue de Saint-Mandé), have invented a new and useful Generator for Electric Lamps, which improvements are fully set forth in the following specification.

The present invention relates to generators, and in particular to an improved generator which is designed primarily for use in connection with or as a part of a pocket or other portable electric lamp, or of a stationary lamp, and in which the current is derived from a magneto or alternator included in the structure in place of the more usual battery or accumulator.

An embodiment of the invention is illustrated in the accompanying drawings, in 20 which:—

Figures 1 and 2 are vertical sectional views at right angles to each other through one form of generator, the sections being taken, respectively, on line 1—1, Figure 2, and 25 line 2—2, Figure 1;

Figure 3 is a vertical sectional view showing a slight modification.

Referring more particularly to the drawings, 1 indicates a multi-polar magnet with 30 poles of alternate sign, loosely mounted on a shaft or spindle 26. This magnet is encircled by an annular armature 5, the pole pieces 6 of which carry the usual coils 7, the parts thus far described being enclosed 35 within a casing comprising sections 8 and 9 which are fastened together by bolts 10.

The driving mechanism of the magnet is contained within the casing 8, and may take various forms, as will be understood. 40 According to the arrangement disclosed, the magnet has fastened to it a pinion 27, preferably driven by planetary gearing, here shown as comprising two gears 28 mounted on two pins or studs which are carried by 45 a disk 29, said gears meshing with a fixed, internally toothed ring 30. Disk 29 may be driven in any suitable manner; for example, it may be provided upon one face with a pivotally mounted pawl 33 which 50 co-operates with a ratchet wheel 32 to which a drum 31 is secured, the drum being rotated in one direction by means of a manually-operated band 34 which is passed over and connected to its periphery, the return move-

ment of the drum being produced by coil 55 spring 35 disposed within the drum and connected at one end thereto. In place of this spring, however, a spring ~~meto~~ of any desired character and indicated generally at 36, in Figure 3 may be used; but in either 60 case, the rotation of the disk 29 will cause the two gears 28 to travel around with it, said gears being rotated at such time owing to their engagement with the fixed ring gear 30 and transmitting their rotation to 65 pinion 27, to which the magnet is directly attached. Various other equivalent devices may likewise be employed, both in general for rotating the magnet, and in particular for driving the planetary gearing, if utilized, 70 while still remaining within the scope of the invention.

I claim as my invention:—

1. In a device of the character described, the combination of a casing; a generator 75 within the casing including a rotatable magnet; and mechanism for rotating said magnet comprising a pinion on the axle of the magnet, a planetary gear train connected to drive said pinion, and operating means 80 for said planetary gear train.

2. In a device of the character described, the combination of a casing; a generator within the casing including a rotatable magnet; and mechanism for rotating said magnet comprising a pinion on the axle of the magnet, a rotatable disk, a pair of gears 85 revolvably mounted on said disk in mesh with said pinion, a ring gear fixed in said casing in mesh with both gears and encircling 90 the same, and means for driving said disk.

3. In a device of the character described, the combination of a casing; a generator within the casing including a rotatable magnet; and mechanism for rotating said magnet comprising a pinion on the axle of the magnet, a rotatable disk, a pair of gears revolvably mounted on said disk in mesh with 95 said pinion, a ring gear fixed in said casing in mesh with both gears and encircling the same, a pinion disposed co-axially with said disk, a pawl-and-ratchet connection between the second-named pinion and said disk to drive the latter from the former, and means for rotating the second-named pinion. 100 105

In testimony whereof I have signed this specification.

SYLVAIN ROSENGART.
